REFRIGERATOR DOOR CONSTRUCTION

John A. Semple, Detroit, Mich., assignor to Nash-Kelvinator Corporation, Detroit, Mich., a corporation of Maryland

Application July 16, 1948, Serial No. 39,040

3 Claims. (Cl. 20—38)

1

This invention relates generally to refrigerators and more particularly to refrigerator cabinet door construction.

One of the objects of the present invention is to provide for a refrigerator cabinet, an improved door construction to meet the problems of warpage and ill fits of large doors of the size which extend substantially the full width and height of the cabinet.

Another object of the invention is to provide a large refrigerator door of such rigid construction as will insure its continued true ness, yet one which is not undesirably heavy or bulky in construction.

Another object of the invention is to provide an improved refrigerator door of the above mentioned character which is inexpensive to manufacture and one whose parts may be readily assembled.

Further objects and advantages of the present invention will be apparent from the following description, reference being had to the accompanying drawings, wherein a preferred form of the present invention is clearly shown.

In the drawings:

Fig. 1 is a front view of a refrigerator, partially broken away to show my improved door construction;

Fig. 2 is a broken view in horizontal cross section of the door, taken along the line 2—2 of Fig. 1;

Fig. 3 is a fragmentary sectional view of the door, taken along the line 3—3 of Fig. 2;

Fig. 4 is a fragmentary sectional view of the door, taken along the line 4—4 of Fig. 3;

Figs. 5 and 6 are cross sectional views of the door, taken respectively along the lines 5—5 and 6—6 of Fig. 2; and

Fig. 7 is a broken, rear view of the door.

Referring to the drawings, the refrigerating apparatus shown is of the household type having a cabinet, designated generally by the numeral 20. The cabinet 20 has a food storage compartment 21 which extends substantially from top to bottom thereof so as to use substantially all of the volumetric capacity of the cabinet for storage space. At the front of the cabinet 20, the storage compartment 21 thereof is provided with a correspondingly large access opening 22 which is closed by a large door, designated generally by the numeral 24; the door 24 extending substantially the full width and height of the cabinet. The door 24 may be hung by hinges 26 to one of the side walls of the cabinet proper. Carried by the door 24 on the inner side thereof is a seal

or gasket 28, which is arranged so as to engage the front surfaces, as at 30, of the side, top and bottom cabinet walls to seal the food storage compartment.

5 The door 24 comprises, in general, an outer casing 32 and a separate inner or back panel 34. These cooperate in forming a hollow door shell within which heat insulation 36 is preferably provided so as to decrease heat leakage into the food storage compartment 21. The door casing 32 is preferably made of thin sheet material, such as sheet steel, and the door panel 34 is preferably made of a low heat conducting sheet material, such as sheet phenolic plastic material.

10 With particular reference to Figs. 2 and 7, it will be seen that the door casing 32 is of dish shape having a top 38, bottom 40 and sides 42. An inturned flange 44 extends around the top, bottom and sides of the casing 32 to reinforce or

15 stiffen the casing and to support the seal 28. The seal 28 is attached to the outer surface of the casing flange 44 adjacent the edges thereof. Preferably, the door casing flange 44 is a continuous flange which is preferably provided with a forwardly bent portion 46 extending entirely therearound to reinforce or stiffen the flange. Any suitable type of fastener (not shown) may be used for attaching the seal 28 to the door casing flange 44. The seal 28 may be made of rubber or similar, displaceable material and may be formed with a base portion 48 and a base overlapping or lip portion 50. These portions of the seal cooperate to form a channel to receive an outer marginal portion of the door rear panel 34 and hold the same to the door casing 32.

20 In accordance with my invention, I reinforce the door casing 32 and hold it in desired true shape against warpage by providing therefor a tie or cross member 52 and by providing diagonally crossed tie member 54. The cross member 52 is located preferably substantially midway between the top and bottom of the door casing 32 and has rearwardly extended T-shaped end portions 56 secured to the inner surfaces of the door casing flange 44 at opposite sides of the door. These T-shaped end portions 56 of the cross member 52 oppose twisting action of the cross member and in so doing oppose door warpage. As shown more clearly in Fig. 2, the cross portions 25 of the T-ends are of channel section for increased stiffness of the cross member ends. For rigidity, the cross member 52 is preferably of channel section and to facilitate its assembly with the door casing 32, I make the cross member 52 in two sections comprising, a relatively long, main sec-

30 tion 58 and a short, rear section 60. The rear section 60 is provided with a shoulder 62 which is received in a shoulder 64 formed in the inner surface of the door casing flange 44. The main section 58 is provided with a shoulder 66 which is received in a shoulder 68 formed in the inner surface of the door casing flange 44. The cross member 52 is secured to the door casing 32 by rivets 70 or the like.

tion 60 and a relatively short end section 62. As shown more clearly in Fig. 3, the cross member sections 60 and 62 are arranged in telescopic relationship with each other and may be rigidly secured together by self threading sheet metal screws 64 or by any other suitable means. Also, sheet metal screws 66 may be used to secure outward flanges of the sections 60, 62 to the in-turned flanges 44 of the door casing.

Welded, or otherwise secured to the casing flange 44 adjacent top and bottom corners of the door casing are gussets 67 to which the outer ends of the crossed tie members 54 may be secured by screws 68 or by other suitable means. Screws 70 or other suitable means may be used to secure the crossed tie members 54 together intermediate their ends where they cross each other. To further increase the rigidity of the door casing structure, I arrange the horizontal cross member 52 slightly above the point of crossing of the tie members 54 and secure the cross member separately to each of the tie members 54 as shown, for example, in Fig. 7, but it will be apparent that, if desired the cross member 52 may be located below the point of crossing of the tie members 54 and obtain the same structural result. A reinforcing member 72 is provided for the cross member 52, intermediate the ends of the latter, where member 52 is crossed by the tie members 54. Preferably the reinforcing member 72 is of channel section of a size to be received snugly in the channel cross member 52 to form therewith a rigid box section, as shown in Fig. 6. Screws 74 or other suitable securing means may be used to secure the tie members 54 rigidly to the reinforcing member 52, intermediate the ends of the latter, where member 52 is crossed by the tie members 54.

In addition to reinforcing the door casing 32, I utilize the cross member 52 as a mounting for a door latch mechanism, designated generally by the numeral 76. Any suitable type of door latch mechanism may be employed, the present latch mechanism having a retractable latch member 78 adapted to engage a keeper 80 which is mounted on the cabinet proper. A suitable door handle 82 may be provided and be operatively connected to the latch member 78 for retracting the same. The latch member 76 is enclosed in a casing 84 which may have an out-turned flange 86 which may be secured by screws 88 to in-turned flanges 90 of the cross member 52. Thus, it will be seen that the latch mechanism 76 and the cross member 52 may be a sub-assembly which may be conveniently assembled as such with the door casing 32.

In assembling the door 24, the door casing 32 is placed in a holding fixture (not shown) for holding the casing true while the tie and cross members are assembled therewith. The cross member 52 and the crossed ties 54 are secured at their ends to the casing and to each other to hold the casing in the desired true form. The cross member sections 60, 62 are individually assembled with the casing 32 and are thereafter secured together by the screws 64. This sectional construction of the cross member 52 facilitates positioning of its ends 56 past the door casing flange portion 46. By providing the crossed ties attached to the corners of the door casing and to each other and by providing a cross member tying the casing sides together and to the crossed ties, it will be seen that the true of the door will be retained and that the seal will make good sealing contact with the front of

the cabinet to insure a tight fitting door. It will also be seen that I have provided for reinforcing a thin sheet metal door casing against distortion without need of using a bulky, heavy frame and that the nature of the door structure provides for ready and inexpensive door assembly. In addition, I have provided, a door reinforcing structure of such character as to serve also for supporting a door latch mechanism.

Although only a preferred form of the invention has been illustrated, and that form described in detail, it will be apparent to those skilled in the art that various modifications may be made therein without departing from the spirit of the invention or from the scope of the appended claims:

I claim:

1. In a refrigerator cabinet door, a sheet material door casing having top, bottom and sides formed with an inturned flange, a channel section cross member having opposite ends secured to said flange tying opposite sides of the casing together, a pair of crossed tie members secured to said flange adjacent the corners of said casing, a channel reinforcing member inserted in and intermediate the ends of said cross member forming a box section therewith, and means securing said crossed tie members to said reinforcing member at points spaced from the point of crossing of said tie members.

2. In a refrigerator door, a rectangular door casing, a pair of crossed tie members secured at opposite ends thereof to and respectively adjacent diagonally opposite corners of said casing, a channel cross member secured at opposite ends thereof respectively to opposite side edges of said casing in spaced relation to the intersection of said crossed tie members, and a channel reinforcement complementary to and received in said channel cross member secured to said crossed tie members.

3. In a refrigerator cabinet door, a sheet material door casing having top, bottom and sides formed with an inturned flange, a channel section cross member having opposite ends secured to said flange tying opposite sides of the casing together, a pair of crossed tie members secured to said flange adjacent the corners of said casing, a channel reinforcing member carried solely by said cross member forming a box section therewith, and means securing said crossed tie members to said reinforcing member at points spaced from the point of crossing of said tie members.

JOHN A. SEMPLE.
